UNITED STATES PATENT OFFICE.

CHARLES G. REERS, OF JERSEY CITY, NEW JERSEY.

DEVICE FOR DRAWING ALE.

SPECIFICATION forming part of Letters Patent No. 534,914, dated February 26, 1895.

Application filed December 12, 1894. Serial No. 531,557. (No model.)

To all whom it may concern:

Be it known that I, CHARLES G. REERS, of Jersey City, in the county of Hudson and State of New Jersey, have invented a new and Improved Device for Drawing Ale, of which the following is a full, clear, and exact description.

The object of the invention is to provide a new and improved device for conveniently and quickly drawing the desired amount of ale from a barrel, into a glass or other receptacle without causing the ale to foam at the delivery end.

The invention consists of certain parts and details and combinations of the same, as will be fully described hereinafter and then pointed out in the claims.

Reference is to be had to the accompanying drawings, forming a part of this specification, in which similar letters of reference indicate corresponding parts in all the views.

Figure 1 is a side elevation of the improvement as applied, with parts in section. Fig. 2 is a sectional side elevation of the receptacle and parts connected therewith. Fig. 3 is a sectional plan view of the same, on the line 3-3 of Fig. 2; and Fig. 4 is a similar view of the same, on the line 4-4 of Fig. 2.

The improved device for drawing ale is provided with a receptacle A, made of suitable size and material. In this receptacle A is arranged a partition B forming the compartments A' and A'', of which the former serves to store the ale, and the one above it, A'', is adapted to receive the ale from the storage barrel or cask, as hereinafter more fully described. As shown in Fig. 2, I prefer to put in a second partition B' in the upper part of the receptacle A, to form a third compartment A''' for carrying off air and gases through an air and gas vent, as hereinafter more fully explained.

Into the receptacle A and near to the bottom thereof, extends the pipe C, provided on the outside of the receptacle with a valve C' which is normally open. The pipe C is provided at its upper end with a draw faucet D located on the side of the bar E, so as to be within reach of the operator to draw ale into a glass or other receptacle whenever required.

50 Into the compartment A'', discharges a pipe F provided with a pressure regulating valve G, of any approved construction, the said pipe

F being preferably provided with two or more branch pipes F' and F'' each connected with a pipe I leading to and extending into the barrels, casks or other vessels containing the ale. Each of the pipes F' and F'' is provided with a suitable valve F''' or F'''' which, when opened, connects the corresponding pipe F' or F'' with the main supply pipe I of a barrel containing a particular brand of ale. Each pipe I forms a suction pipe for an ale pump J of any approved construction and located at the bar E. This pump J is only used in case the ale in the barrel is without pressure and must be pumped up; and in this case the corresponding valve F''' or F'''' is closed to disconnect the pipe F and receptacle A from the pipe I.

Each of the partitions B and B' is provided at its edge with notches or openings B² and B³ respectively, so that ale entering the compartment A'', for instance, by the pipe F is distributed over the partition B, to finally pass through the openings or notches B² down the inner face of the receptacle A in the upper part of the compartment A' to fill the latter with the liquid. Now it will be seen that any foam contained or produced in the compartment A'' does not pass into the compartment A', owing to the smallness of the notches in the partitions B and B' which fit directly against the inner wall of the compartment A. Foam which rises and fills the compartment A'' can pass through the notches B³ into the compartment A'', and as the foam condenses there the liquid can flow through the notches B³ down the inner wall of the compartment A'' to fill the same, and finally pass through the notches into the compartment A'.

From the upper compartment A''' leads an air and gas vent pipe H, provided with a valve H', near the receptacle A, and normally open. The upper end of the pipe H, which extends to the bar E is provided with a valve H'', normally closed but opened from time to time by the bar keeper, to let out air and gas accumulated in the receptacle A, and to permit the ale to pass by its own pressure into the receptacle from the barrel by pipes I F and regulating device G. The receptacle A is preferably provided with a glass gage K, of any approved construction, so that the amount of ale contained in the receptacle can be ascertained at any time.

The operation is as follows: When it is desired to draw ale into a glass or other receptacle at the bar E, the operator opens the draw faucet D and the ale under its own pressure flows from the compartment A' through the pipe C into a glass. The ale withdrawn from the receptacle, is replaced by ale from the pipe F and regulator G flowing into the compartment A². In doing so the ale produces foam which, however, does not pass into the lower compartment A', as previously explained, but only the liquid, so that ale without foam is drawn from the bottom of the receptacle through the pipe C whenever the faucet D is opened. The foam in the compartments A² and A³ condenses, as ale is not continuously drawn by the faucet and the liquid thus produced accumulates in the compartment A' as previously explained. The barkeeper, from time to time, opens the valve H², so as to let out the gases formed by the condensation of the ale or the evaporation thereof, and to permit the refilling of the receptacle A should the latter run low by drawing large quantities.

It will be seen that by the arrangement described, ale is drawn directly into the glass or other receptacle at the bar without causing any or much foam, so that it requires but a short time to fill the glass. As is well known, ale as heretofore drawn from the storage cask, produces considerable foam at the delivery end of the ale pump, and the usual practice heretofore was to draw an amount of ale into a supply vessel, from which to fill the glasses as called for.

Having thus fully described my invention, I claim as new and desire to secure by Letters Patent—

1. A device for drawing ale, comprising a receptacle having an inlet adapted for connection with the barrel, and provided with an

outlet, and an essentially imperforate partition whose edge is secured to the walls of the receptacle between the inlet and outlet pipe, 45 said partition being provided with notches near the walls of the vessel, substantially as described.

2. A device for drawing ale, comprising a receptacle provided with a marginally notched 50 partition forming two compartments, an inlet pipe discharging into the receptacle above the partition and essentially parallel thereto, to cause the ale to spread over the partition, and an outlet pipe connected to the lower 55 compartment, substantially as described.

3. A device for drawing ale, comprising a receiving receptacle connected with the barrel and draw faucet, a partition fitting in the said receptacle between the inlet and outlet 60 pipes, the said partition being provided with notches to cause the entering ale to flow through the notches onto the inner face of the receptacle below the partition, and a second notched partition above the inlet pipe to 65 form a vent chamber in the said receptacle, substantially as shown and described.

4. A device for drawing ale, comprising a receiving receptacle connected with the ale barrel or cask, a partition fitting in the said 70 receptacle between the inlet and outlet pipes, the said partition being provided with notches to cause the entering ale to flow through the notches onto the inner face of the receptacle below the partition, a second notched partition above the inlet pipe to 75 form a vent chamber in the said receptacle, and a vent pipe leading from the said vent chamber and provided with a valve, substantially as shown and described.

CHARLES G. REERS.
